DIE STAMPING PRESS AND DIE WIPER
THEREFOR

Robert N. Steffens, Essex Fells, N. J.

Application March 22, 1947, Serial No. 736,555

19 Claims. (Cl. 101—166)

1

This invention relates to die stamping presses and die wipers therefor, and a method of cleaning an element of said press.

In die stamping presses for making imprints on papers from intaglio engraved plates and dies, the plate or die is automatically coated with ink on the entire die surface and the die is then passed across a wiping pad which is adapted to remove all of the ink except the ink retained in the engraved design lying below the die or plate surface. After being wiped, the die is brought into printing position and by means of pressure, the inked-in design is transferred to paper to form the finished print.

In machines now in use, an endless strip of material, which is preferably non-absorbent, is arranged on the machine so that it is fed over the wiping pad and is advanced with each printing operation. This permits a clean wiping surface to be continuously presented for the removal of excess ink from the die. The ink covered portions of the wiper strip pass through a solvent bath and are subjected to the action of scrapers which remove the ink from the strip. This arrangement permits the presentation of a clean, ink-free portion of the wiper strip at its wiping position. Inasmuch as the wiper strip or belt is of substantial length, idler rolls and the like have been used to take up slack portions of the wiper strip. However, arrangements of this type have not permitted the wiper strip to function at its highest efficiency, particularly as regards the removal of all surplus ink from the die face.

Accordingly, it is an object of this invention to provide a die wiper of the endless belt type wherein a section of the belt passing over the wiper pad, is positively tensioned, thereby removing the ink from the die surface more efficiently and furthermore withstanding the friction of the sliding die while the ink is being removed by the belt.

A further object of this invention is to provide in an endless belt wiper for a die stamping press combined with scraping elements and a solvent bath to remove surplus ink and ink solvent from the belt, means for suitably tensioning those portions of the belt passing over the scraping elements, thereby increasing the efficiency of said scraping elements.

Yet another object of this invention is to provide means for tensioning a relatively small section of a relatively long, endless wiper belt. The tensioned section of the belt being that portion immediately adjacent the wiping pad of a die press and solvent means adapted to remove surplus ink carried on the belt from the wiped die. The untensioned portion of the belt may be of such length as to permit adequate exposure of

2

the belt after its treatment with solvents incident to the removal of ink.

Still another object of this invention is to provide means for feeding an endless wiper belt through a die press wherein the feeding means comprises a pair of feed rolls located on one side of a wiper pad and a pair of wringer rolls on the other side of the wiper pad, the peripheral speed of the wringer rollers being slightly greater than that of the feed rollers whereby that portion of the belt lying between the feed rollers and the wringer rollers, is suitably tensioned.

Still another object of this invention is to provide a highly improved die stamping press combined with a die wiper belt arrangement which shall be relatively inexpensive to manufacture, smooth and positive in operation and yet practical and efficient to a high degree in use.

Other objects of this invention will in part be obvious and part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible illustrative embodiments of this invention,

30 Fig. 1 is a front elevational view of a die stamping press embodying the invention;

Fig. 2 is a rear elevational view of the die stamping press shown in Fig. 1;

Fig. 3 is a top plan view of the die press shown in Fig. 1;

Fig. 4 is an enlarged, front elevational view of portion of the die press with a cover plate removed to show the details of the scraping means and wringer rolls;

40 Fig. 5 is an enlarged elevational view showing the details of an alternative chain drive interconnecting the feed rollers, wringer rollers and the intermittent feed mechanism;

Fig. 6 is a cross-sectional view taken on the line 6—6 of Fig. 4;

Fig. 7 is a cross-sectional view taken on the line 7—7 of Fig. 4;

Fig. 8 is a front elevational view of one of the scraper members;

50 Fig. 9 is an end view of the scraper member illustrated in Fig. 8;

Fig. 10 is a top plan view of the details of the alternative chain drive shown in Fig. 5;

Fig. 11 is a front elevational view of a solvent wiper element and its supporting bracket which is associated with the scraper means as shown in Fig. 4;

Fig. 12 is a front elevational view of the solvent applicator shown in Fig. 4;

Fig. 13 is a cross-sectional view taken on the line 13—13 of Fig. 11; and

Fig. 14 is a cross sectional view taken on the line 14—14 of Fig. 12.

Referring now in detail to the drawing, 10 designates a die stamping press and die wiper embodying the invention. The same comprises a frame 11 on which is mounted the usual horizontally extending bed 12. Extending upwardly from one end of the bed 12, is a channeled member 13 comprising a web 13a and flanges 13b, and extending upwardly from the other end of the bed 12 is a frame 14 from which extends in spaced relation thereto, a pair of parallel aligned arms 14a. Mounted on the frame 11 is a conventional actuating mechanism 15 for imparting reciprocating motion to the usual ram 16 which is slidably mounted on frame 14 for vertical movement relative to the bed 12. The actuating mechanism 15 comprises a gear 17 mounted on a central portion of a shaft 18 journaled on the frame 11 together with a pair of disks 19 secured to either end of the shaft 18. A pair of arms 20 are pivotally attached at their upper ends to the ram 16 and pivotally attached at their lower ends to crank pins secured on the disks 19 and eccentrically mounted with respect to shaft 18. The rotation of shaft 18 will impart oscillating movement to the arms 20 which in turn will cause reciprocating movement of the ram 16. The gear 17 is interconnected to a gear 21 by means of a pinion 22. The gear 21 is mounted on a central portion of a shaft 23 suitably journaled on its frame 11. Secured to the rear end of shaft 23 is a circular member 24 to which is secured a cam follower 25 in eccentric relation to the shaft 23. The follower 25 engages an eccentrically shaped groove portion 26 of an arm 27 pivotally secured at its lower end to a base portion of the frame 11 thereby imparting oscillating motion to the arm 27. The upper end of the arm 27 is pivotally connected to an arm 28 which in turn is connected to a die 29 slidably mounted for horizontal movement on the bed 12. It is understood that the movement of the ram 16 and the die 29 is correlated to produce the desired stamping action in a manner well known in the art.

Means is provided for applying ink to the reciprocating die. To this end an ink containing pan or receptacle 30 is positioned on the bed 12 adjacent the channeled member 13. A rotating roll 31 mounted in the pan 30 is adapted to transfer ink within the pan to a transfer roller 32 which is mounted on the end of an oscillating arm 33 which is pivotally mounted on a lower end of the frame portion 14a. Oscillating motion is imparted to the arm 33 by means of a bell crank 34 pivotally mounted on the frame 11 and having one arm 35 bearing against an eccentric cam 36 secured to the shaft 18. The other arm 37 of the crank 34 is pivotally connected to an upwardly extending arm 38 which in turn is pivotally connected to a short arm 39, which in turn is pivotally connected to the arm 33. The end portion of the arm 37 of bell crank 34 is biased in a downward direction by means of a spring 40 having one end attached to the arm 37 and the other end secured to the base of the frame 11. It will be apparent that the rotary motion of the cam 36 will impart oscillating movement to the bell crank 34 which in turn will cause the arm 33 to move to and from a

position where the roller 32 is caused to contact the roller 31, thereby effecting the transfer of ink to the roller 32. The movement of the arm 33 is correlated to the movement of the die 29 whereby the ink coated roller 32 will contact the surface of the die 29 at a retracted position during its pivoted movement over the bed 12.

A conventional wiper pad 41 is mounted on the bed 12 adjacent the lower end of the ram 16. Means is provided to feed an endless wiper belt 42 around the wiper pad 41. To this end there is journaled on a projecting inner portion of the frame 14, a shaft 43 on which is secured a roller 44. An opposed roller 45 is suitably journaled in bearing blocks 46 slidably mounted on the frame and is resiliently pressed towards roller 44 by means of springs 47 and adjusting screws 48 mounted on overlying projections of frame 14. A roller 49 is rotatably mounted on the upper extremity of the frame 14, for the purpose hereinafter described.

The feed roller 44 is adapted to be rotated intermittently in a clockwise direction. To this end, a sprocket wheel 50 secured to one end of the shaft 43 is interconnected to a sprocket wheel 51 secured to a shaft 51a journaled on the upper end of the front arm 14a, by means of a chain 52. The sprocket wheel 51 is interconnected to the gear 21 by means of a crank arm 53, one end of which is eccentrically mounted with respect to the gear shaft 23, the other end of the crank arm 53 being pivotally connected to one end of a swivel member 54. The other end of the swivel member 54 is pivotally mounted on the outer end of the shaft 51a on which is also secured a ratchet wheel 56. A pawl 58 on the swivel member 54, engages the ratchet wheel 56. It will be apparent that each revolution of the gear 21 will cause the crank arm 53 to move up and down, thereby actuating the pawl 58 through an angle of about 90 degrees. The pawl 58 will move the ratchet wheel 56 together with the sprocket wheel 51, on its upward movement and will slide back on its downward movement without moving the ratchet wheel. This in turn will cause the roller 44 to rotate in a clockwise direction intermittently through its interconnection with the sprocket wheel 51. The intermittent movement of the roller 44 and its associated roller 45 will produce intermittent movement of the belt 42 passing between the rollers.

Means is also provided to tension a selected section of the belt 42 as it moves through the die press.

To this end there is provided a pair of horizontally extending aligned frame members 59 which are secured at their inner end portions to the channel member 13. Each frame member 59 comprises a pair of vertically spaced, parallel arms 60 interconnected at their outer ends by vertical arms 61, the inner end of each upper arm 60 being secured to the flange 13b of channel member 13 by means of screws 61a. The inner edge portion of each arm 60 is formed with a groove 62 and spaced therefrom a groove 63. Mounted within the opposed grooves 63 in arms 60 is a pair of bearing blocks 64 on which is rotatably mounted a shaft 65 to which is secured a roller 65a. A second roller 66a, axially aligned with roller 65a, is secured to a shaft 66 rotatably mounted in a pair of bearing blocks 67, slidably mounted within the opposed grooves 62 in arms 60. The blocks 67 are interconnected by a member 68 which extends in spaced, parallel relationship to the roller 66a. An adjusting screw 69

extends through a threaded opening in a central portion of the web 13a of the channel member and bears against the member 68. By turning the screw 69, the spacing between the rollers 65a and 66a may be suitably adjusted. The ends of shafts 65 and 66 project through their respective bearing blocks and aligned through openings in a pair of spaced parallel cover plates 70 which are secured to the channelled member 13 on the outer sides of flanges 13b, by screws 61b. The plates 70 are also secured to the outer end portions of the arms 60 by screws 70a. The cover plates 70 are formed on central portions of their inner surfaces with aligned projecting bosses 70b, for the purpose hereinafter described. Secured on each of the shafts 65 and 66 on their end portions, are pairs of meshing gears 71, 72. On the shaft 65, adjacent the gear 72, is secured a sprocket wheel 73 which is interconnected to a sprocket wheel 74 secured to the rear end of shaft 60, by means of a sprocket chain 75. It will be apparent that the intermittent clockwise rotation of the roller 44 will cause similar intermittent clockwise rotation of the roller 65a and counterclockwise rotation of roller 66a. The relative diameters of the sprocket wheels 74 and 73 are so related that the peripheral speed of roller 65a is slightly greater than the peripheral speed of the roller 44. This produces a tension in that portion of the belt 42 which extends from the rollers 44, 45 around the wiper pad 41 to the rollers 65a, 66a.

Means is also provided to remove surplus ink from the belt 42 as it moves away from the wiper pad 41 towards the rollers 65a, 66a. To this end there extends from the channel member 13 and below the frame 59 a pair of parallel supporting arms 175, in parallel relationship to the bed 12. The lower edge of the cover plates 70 is secured to the outer end of the arms 175 by means of screws 76. A receptacle 77 for ink solvent or the like is disposed between the arms 175. Mounted on the inner side of each of the cover plates 70 is a pair of brackets 77a. The brackets 77a are of generally rectangular shape and comprise a downwardly extending triangular portion 78, an upwardly inclined arm portion 79 opposite the triangular portion 78 and a spaced portion 80 overlying an upper edge of the bracket and forming an upwardly inclined rectangular shaped, open ended slot 81. The arm 79 is also formed with a rectangular shaped open ended slot 82. The right hand portion of the bracket 77a, looking at Fig. 4, is formed with rectangular shaped open ended slots 83, 84 which extend upwardly and are inclined outwardly of each other. The brackets 77a are further formed with projecting bosses 85 on outer surfaces thereof. The brackets 77a are disposed adjacent the cover plates 70 with the bosses 85 abutting the bosses 70a on the cover plates 70 and secured thereto by means of screws 86 passing through the cover plates 70. The slots 81, 82, 83 and 84 in the brackets 77a are adapted to receive similar scraper members 81a, 82a, 83a and 84a, respectively. The scraper members comprise elongated rectangular plates 88 to which are secured in overlying relationship thereto, a scraper blade 89 which projects beyond the upper edge of plate 88. A thin cover plate 90 overlies the blade 89 and spaced screws 91 secure the cover plate 90 and the blade 89 to the plate 88. The scraper members are adapted to be readily inserted in the aligned slots 81, 82, 83 and 84 and are easily removed when necessary. A roller 92 is rotatably journalled between the triangular portions 78 of the bracket 77a. The roller 92

is adapted to extend into the lower portions of the solvent containing receptacle 77.

It will be noted from a consideration of Fig. 4, that during the movement of belt 42, it is adapted to contact the successive scraper members 84a, 83a, pass around the roller 92 and move upwardly, contacting scraper members 81a, 82a. The belt 42 then continues its upward movement, passing between rollers 65a, 66a. The path of travel of the belt 42 from the wiper pad 41 towards the bracket 77a is deflected in a manner which sharply reflexes the belt as it passes around the scraper member 84a.

The belt is again sharply flexed as it passes over scraper 83a when its path is again deflected in its downward movement towards the roller 92. As the belt 42 continues around the roller 92 and moves upwardly, it is scraped by scrapers 81a, 82a and is flexed across the blade of the scraper by reason of the overlapping position of the scraper 82a with respect to scraper 81a as shown in Fig. 4. It is apparent that the scrapers 84a, 83a will remove surplus ink on the under surface of the tensioned belt 42, the ink receptacle 30 which is positioned under the scrapers, receiving the thus removed ink. The solvent contained within the receptacle 77, dissolves any remaining ink on the belt 42 as it is deeply immersed in the solvent during its passage through the container 77. The scrapers 81a, 82a remove the excess solvent from either side of the belt 42, the receptacle 77 receiving the drippings. The rollers 65a, 66a also act to squeeze any residual solvent from the belt with the drippings also going back into the receptacle 77.

The upper end of the channelled member 14 has journalled thereon a pair of vertically aligned idler rollers 93, 94. The belt 42 moves upwardly over roller 93 and around roller 94, then continuing around idler roller 94 to pass between feed rollers 45, 44. A floating, weighted roller 95 is used to take up surplus slack in the belt between idler rollers 93 and 94.

It will be apparent that the section of the wiper belt 42 which passes around the wiper pad 41 will be tensioned in a manner to facilitate its wiping action with respect to the reciprocating die 29. In this manner, all surplus ink will be removed from the die surface by the wiper belt. The action of the scrapers 81a, 82a, 83a and 84a as well the rolls 65a, 66a is also facilitated by the tensioning of the belt 42. The squeezing pressure of roll 66a with respect to roll 65a is regulated by means of the screw 69. This adjustment also permits regulation of the spacing between the rolls to accommodate belts of different thicknesses.

In Fig. 5 is shown an alternative form of chain drive in which the rollers 65a, 66a are connected directly to the sprocket wheel 51 which is actuated by the ratchet wheel 56, instead of indirectly by way of the roller 44 as shown in Fig. 1. A sprocket wheel 74a is secured to the rear end of shaft 51b which is journalled on arms 14a and is interconnected to sprocket wheel 73 by a sprocket chain 75a. The sprocket wheel 51 secured on the front end of shaft 51b is interconnected to the sprocket wheel 50 by sprocket chain 52, as previously described. The intermittent rotation of the sprocket wheel 51 will thus cause similar rotation of the sprocket wheel 73 and the associated rollers 65a, 66a.

It will be apparent that a relatively small section of the wiper belt 42 is tensioned by reason of the indicated arrangement of the rollers 65a, 66a relative to the feed rollers 44, 45. This also

permits a relatively large section of the un tensioned portion of the belt to pass over idler rollers, thereby facilitating the evaporation of any solvent retained by the belt after passage through the rollers 65a, 66a, towards the feed rollers 44, 45.

In order to insure the removal of ink from the belt 42 as it leaves the wiper pad 41, there is provided means for supplementing the action of the scrapers 83a and 84a. To this end, a pair of similar brackets 100 are bolted at one end to the brackets 77a, adjacent the slot 84 therein. The brackets 100 are inclined downwardly and outwardly and are formed on their other ends with open ended, vertically extending, slots 101. A combination solvent receptacle and solvent applying means 102 is adjustably mounted on the slotted portions of the brackets 100. The receptacle and applying means 102 comprises a trough shaped receptacle 103 having a vertical wall 104 and an inclined wall 105. The receptacle 102 is bolted to an open top casing 106. The casing 106 comprises a pair of similar, parallel side walls 107, 108, a pair of end walls 109 which extend above the side walls and a bottom wall 109a. The end walls 109 are formed with aligned slots 110 on their upper ends. A shaft 111 is journaled in the slots 110 and has secured thereto a roller 112. A set of wicks 113 which project above the walls 107, 108 are contained within the casing 106, the upper ends thereof being in contact with the roller 112. The lower portion of wall 104 of receptacle 103 is formed with spaced openings 114 which are aligned with similar openings 115 in the adjacent wall 107 of the casing. The end walls 109 are provided with vertically aligned, spaced threaded studs 116 which are disposed in the slots 101 of the brackets 100. Nuts 117 which span the slots 101, are screwed on the studs 116 to adjustably position the combination receptacle and applying means 102 with respect to the brackets 100. A conduit 118 extending from a lower portion of the solvent receptacle 77 to the receptacle 103 provides the latter with a supply of solvent from the former. The aligned openings 114, 115 in the receptacle 103 and casing 106, respectively, permits the passage of solvent into the casing 106, thereby saturating the wicks 113 which in turn apply the solvent to the roller 112. The roller 112 which is disposed in the path of travel of the belt 42 as it leaves the wiper 41 and approaches the scraper 84a, will apply solvent to the underside or ink coated surface of the belt, thereby softening and loosening the dried coating. This will facilitate the subsequent scraping action of the scrapers 84a, 83a, as previously described.

Means is also provided for facilitating the application of solvent to the belt 42 as it passes through the solvent receptacle 77. To this end a channel shaped member 119 is mounted on the bracket 77a. The member 119 comprises a pair of parallel arms 120 interconnected by a web 121. The member 119 is secured to the brackets 77a by means of screws 122 passing through openings in the upper ends of the arms 120 and received in threaded openings in the bracket 77a, disposed below the slots 81 thereof. The web 121 of the member 119 is disposed adjacent the bottom of the solvent receptacle 77 and the roller 92. A felt member 122 is clamped between the web 121 and an overlying plate 123 which is removably secured to the web 121 by screws 124. The felt member 122 comprises a folded edge portion 125 which is adapted to

frictionally engage the belt 42 as it passes around the roller 92. The edge portion 125 of the felt member by reason of a rubbing action enhances the effect of the solvent in the receptacle 77 in removing any residual ink on the belt 42.

The rollers 65a, 66a as well as the rollers 44, 45 are made of smooth metal. It is understood that the higher speed of the rollers 65a, 66a as compared to that of rollers 44, 45 will stretch the belt 42 moving between the rollers to a point at which the driving friction of the rollers is exceeded by the resisting tension of the belt. At this point the smooth metal rollers merely slip on the belt surface without injury to the belt surface.

The wiper belt 42 may be made of thermoplastic materials such as the vinyl resins or chemically modified rubbers. These materials are particularly adapted for use as die wiper belts 20 inasmuch as they do not absorb ink; are readily washed free of ink and are inert with respect to ink solvents. Such materials are also resistant to moisture and are readily seamed when it is necessary to make a joint in the belt.

It will thus be seen that there is provided a device in which the several objects of this invention are achieved, and which is well adapted to meet the conditions of practical use.

As various possible embodiments might be 30 made of the above invention, and as various changes might be made in the embodiment above set forth or shown in the accompanying drawing is to be interpreted as illustrative and not in a limiting sense.

Having thus described my invention I claim as new and desire to secure by Letters Patent:

1. In a machine for printing engraved stationery, an endless die wiper belt, means to tension a selected portion of the belt substantially 40 less than the whole length of the belt, a die, means for contacting the die with the tensioned portion of the belt to remove ink from the die, means to scrape ink off a part of the tensioned portion of the belt which has removed ink from the die, and means to apply ink solvent to a part of the tensioned portion of the belt after the belt has been scraped by said scraping means, and said tensioning means comprising means to wring said belt after solvent has been 50 applied to said belt, and said tensioning and wringing means comprising means to advance said belt.

2. In a machine for printing engraved stationery, an endless die wiper belt, means to tension a selected portion of the belt substantially less than the whole length of the belt, a die, means for contacting the die with the tensioned portion of the belt to remove ink from the die, means to apply ink solvent to a part of the tensioned portion of the belt after the belt has 60 wiped the die, said tensioning means comprising means to wring said belt, and said tensioning and wringing means comprising means to advance said belt.

3. In a machine for printing engraved stationery, an endless die wiper belt, means to tension a selected portion of the belt, a die, means for contacting the die with the tensioned portion of the belt to remove ink from the die, means to scrape ink off a part of the tensioned portion of the belt which has removed ink from the die, means to apply ink solvent to a part of the tensioned portion of the belt after the belt has been scraped by said scraping means, and 70 means to scrape ink solvent and dissolved ink 75

from the belt after ink solvent has been applied thereto, and said tensioning means comprising means to wring said belt after said last mentioned scraping means has scraped solvent and dissolved ink from the belt, and said tensioning and wringing means further comprising means to advance said belt.

4. In a press for printing engraved stationery, an endless die wiper belt, means for advancing the belt and tensioning a selected portion of the belt of less length than the remaining portion of the belt, means to maintain said remaining portion of the belt under less tension than the tensioned portion, a die wiper pad contacted by said tensioned portion of the belt, means for scraping a portion of the tensioned part of the belt which has contacted the pad, means to apply ink solvent to the part of the tensioned portion of the belt which has contacted the pad and has been scraped, means to scrape the belt after ink solvent has been applied thereto to remove solvent and dissolved ink therefrom, and said tensioning and advancing means comprising means to wring said belt after it has been scraped by said last mentioned scraping means.

5. In a press for printing engraved stationery, a die wiper pad, an endless belt having a portion contacting the wiper pad, a pair of opposed rollers on opposite sides of the belt and in advance of the pad, means to press said rollers against opposite sides of the belt, means to rotate one of said rollers to feed the belt forwardly past the wiper pad, a second pair of opposed rollers contacting opposite sides of the belt in back of the wiper pad, means to press said rollers against opposite sides of the belt, and means to rotate one of said second pair of rollers at a peripheral speed less than that of the first pair of rollers to feed the belt forwardly toward the wiper pad, whereby the portion of the belt moving forwardly from the second pair of rollers to the first pair of rollers is under tension, the tensioned portion of the belt being less in length than the remaining portion of the belt, and means to maintain said remaining portion of the belt at less tension than said tensioned portion, and intermeshing gears on said first pair of rollers, means to scrape a portion of the tensioned part of the belt between the wiper pad and the first pair of rollers, a bath of ink solvent located beneath the scraper means, and means to pass a portion of the belt through said bath after it has been scraped.

6. In a press for printing engraved stationery, a die wiper pad, an endless belt having a portion contacting the wiper pad, a pair of opposed rollers on opposite sides of the belt and in advance of the pad, means to press said rollers against opposite sides of the belt, means to rotate one of said rollers to feed the belt forwardly past the wiper pad, a second pair of opposed rollers contacting opposite sides of the belt in back of the wiper pad, means to press said rollers against opposite sides of the belt, and means to rotate one of said second pair of rollers at a peripheral speed less than that of the first pair of rollers to feed the belt forwardly toward the wiper pad, whereby the portion of the belt moving forwardly from the second pair of rollers to the first pair of rollers is under tension, the tensioned portion of the belt being less in length than the remaining portion of the belt, and means to maintain said remaining portion of the belt at less tension than said tensioned portion, intermeshing gears on said first pair of rollers, and means to scrape a por-

tion of the tensioned part of the belt between the wiper pad and the first pair of rollers, a bath of ink solvent located beneath the scraper means, means to pass a portion of the belt through said bath after it has been scraped, and said first pair of rollers being located above said bath.

7. In a press for printing engraved stationery, a die wiper pad, an endless belt having a portion contacting the wiper pad, a pair of opposed rollers on opposite sides of the belt and in advance of the pad, means to press said rollers against opposite sides of the belt, means to rotate one of said rollers to feed the belt forwardly past the wiper pad, a second pair of opposed rollers contacting opposite sides of the belt in back of the wiper pad, means to press said rollers against opposite sides of the belt, and means to rotate one of said second pair of rollers at a peripheral speed less than that of the first pair of rollers to feed the belt forwardly toward the wiper pad, whereby the portion of the belt moving forwardly from the second pair of rollers to the first pair of rollers is under tension, the tensioned portion of the belt being less in length than the remaining portion of the belt, and means to maintain said remaining portion of the belt at less tension than said tensioned portion, and intermeshing gears on said first pair of rollers, means to scrape a portion of the tensioned part of the belt between the wiper pad and the first pair of rollers, a bath of ink solvent located beneath the scraper means, means to pass a portion of the belt through said bath after it has been scraped, said first pair of rollers being located above said bath, and a second scraping means for scraping ink solvent and dissolved ink from the belt after the belt has passed through said bath and before said belt reaches the first pair of rollers.

8. In a press for printing engraved stationery, a die wiper pad, an endless belt having a portion contacting the wiper pad, a pair of opposed rollers on opposite sides of the belt and in advance of the pad, means to press said rollers against opposite sides of the belt, means to rotate one of said rollers to feed the belt forwardly past the wiper pad, a second pair of opposed rollers contacting opposite sides of the belt in back of the wiper pad, means to press said rollers against opposite sides of the belt, and means to rotate one of said second pair of rollers at a peripheral speed less than that of the first pair of rollers to feed the belt forwardly toward the wiper pad, whereby the portion of the belt moving forwardly from the second pair of rollers to the first pair of rollers is under tension, the tensioned portion of the belt being less in length than the remaining portion of the belt, and means to maintain said remaining portion of the belt at less tension than said tensioned portion, intermeshing gears on said first pair of rollers, means to scrape a portion of the tensioned part of the belt between the wiper pad and the first pair of rollers, a bath of ink solvent located beneath the scraper means, means to pass a portion of the belt through said bath after it has been scraped, said first pair of rollers being located above said bath, a second scraping means for scraping ink solvent and dissolved ink from the belt after the belt has passed through said bath and before said belt reaches the first pair of rollers, and means to adjust the pressure of each pair of rollers against the belt.

9. In a press for printing engraved stationery, a die wiper pad, a pair of opposed rollers in ad-

vance of the pad, a die wiping strip contacting the pad and passing between the rollers, adjustable means other than the rollers themselves, to press the rollers toward each other and against opposite sides of the wiping strip, intermeshing gears on said rollers, means to rotate said rollers to advance said strip, a second pair of opposed rollers in back of the wiping pad and between which said strip passes, means to press said rollers against opposite sides of the strip, and means including means connecting one of the second pair of rollers with one of the first pair of rollers, to rotate said roller of the second pair at a peripheral speed less than that of the first pair of rollers, to advance said strip toward the wiper pad and whereby the portion of the strip between said first and second pairs of rollers is under tension, and means to remove ink from a portion of the tensioned part of the strip in advance of the pad.

10. In a press for printing engraved stationery, a die wiper pad, a pair of opposed rollers in advance of the pad, a die wiping strip contacting the pad and passing between the rollers, adjustable means other than the rollers themselves, to press the rollers toward each other and against opposite sides of the wiping strip, intermeshing gears on said rollers, means to rotate said rollers to advance said strip, a second pair of opposed rollers in back of the wiping pad and between which said strip passes, means to press said rollers against opposite sides of the strip, means including means connecting one of the second pair of rollers with one of the first pair of rollers, to rotate said roller of the second pair at a peripheral speed less than that of the first pair of rollers, to advance said strip toward the wiper pad and whereby the portion of the strip between said first and second pairs of rollers is under tension, and means to scrape a portion of the tensioned part of the strip at a point between the pad and the first pair of rollers.

11. In a press for printing engraved stationery, a die wiper pad, a pair of opposed rollers in advance of the pad, a die wiping strip contacting the pad and passing between the rollers, means to press the rollers toward each other and against opposite sides of the wiping strip, intermeshing gears on said rollers, means to rotate said rollers to advance said strip, a second pair of opposed rollers in back of the wiping pad and between which said strip passes, means to press said rollers against opposite sides of the strip, means including means connecting one of the second pair of rollers with one of the first pair of rollers, to rotate said roller of the second pair at a peripheral speed less than that of the first pair of rollers, to advance said strip toward the wiper pad and whereby the portion of the strip between said first and second pairs of rollers is under tension, means to scrape a portion of the tensioned part of the strip at a point between the pad and the first pair of rollers, and a bath of ink solvent located beneath the scraper means, and means to pass a portion of the scraped strip through the bath to dissolve ink therefrom.

12. In a press for printing engraved stationery, a die wiper pad, a pair of opposed rollers in advance of the pad, a die wiping strip contacting the pad and passing between the rollers, means to press the rollers toward each other and against opposite sides of the wiping strip, intermeshing gears on said rollers, means to rotate said rollers to advance said strip, a second pair of opposed rollers in back of the wiping pad and between

which said strip passes, means to press said rollers against opposite sides of the strip, means including means connecting one of the second pair of rollers with one of the first pair of rollers, to rotate said roller of the second pair at a peripheral speed less than that of the first pair of rollers, to advance said strip toward the wiper pad and whereby the portion of the strip between said first and second pairs of rollers is under tension, means to scrape a portion of the tensioned part of the strip at a point between the pad and the first pair of rollers, a bath of ink solvent located beneath the scraper means, means to pass a portion of the scraped strip through the bath to dissolve ink therefrom, and means for scraping dissolved ink and ink solvent from the belt after the belt has passed through said bath and before said belt reaches said first pair of rollers.

13. In a press for printing engraved stationery, a die wiper pad, a pair of opposed rollers in advance of the pad, a die wiping strip contacting the pad and passing between the rollers, means to press the rollers toward each other and against opposite sides of the wiping strip, intermeshing gears on said rollers, means to rotate said rollers to advance said strip, a second pair of opposed rollers in back of the wiping pad and between which said strip passes, means to press said rollers against opposite sides of the strip, means including means connecting one of the second pair of rollers with one of the first pair of rollers, to rotate said roller of the second pair at a peripheral speed less than that of the first pair of rollers, to advance said strip toward the wiper pad and whereby the portion of the strip between said first and second pairs of rollers is under tension, means to scrape a portion of the tensioned part of the strip at a point between the pad and the first pair of rollers, a bath of ink solvent located beneath the scraper means, means to pass a portion of the scraped strip through the bath to dissolve ink therefrom, and means for scraping dissolved ink and ink solvent from the belt after the belt has passed through said bath and before said belt reaches said first pair of rollers, and said first pair of rollers being located above said bath.

14. In a press for printing engraved stationery, a die wiper pad, a pair of opposed rollers in advance of the pad, a die wiping strip contacting the pad and passing between the rollers, means to press the rollers toward each other and against opposite sides of the wiping strip, intermeshing gears on said rollers, means to rotate said rollers to advance said strip, a second pair of opposed rollers in back of the wiping pad and between which said strip passes, means to press said rollers against opposite sides of the strip, means including means connecting one of the second pair of rollers with one of the first pair of rollers, to rotate said roller of the second pair at a peripheral speed less than that of the first pair of rollers, to advance said strip toward the wiper pad and whereby the portion of the strip between said first and second pairs of rollers is under tension, means to scrape a portion of the tensioned part of the strip at a point between the pad and the first pair of rollers, a bath of ink solvent located beneath the scraper means, means to pass a portion of the scraped strip through the bath to dissolve ink therefrom, and means for scraping dissolved ink and ink solvent from the belt after the belt has passed through said bath and before said belt reaches

said first pair of rollers, said first pair of rollers being located above said bath, and means to adjust the pressure of each pair of rollers against the belt.

15. In a press for printing engraved stationery, a die wiper pad, an endless die wiper belt contacting the pad, a pair of opposed rollers contacting opposite sides of the belt in advance of the pad, adjustable means to press the rollers toward each other and against opposite sides of said belt, means to rotate one of said rollers to advance said belt forwardly past the wiper pad, a second pair of opposed rollers in back of the wiping pad and contacting opposite sides of the belt, means to press said second pair of rollers toward each other against opposite sides of the belt, means to rotate one of said second pair of rollers at a peripheral speed less than that of the first pair of rollers, to feed the belt forwardly toward the wiper pad, whereby the portion of the belt moving forwardly from the second pair of rollers to the first pair of rollers, is under greater tension than the remaining portion of the belt, a die, means to wipe the die against the portion of the belt which is pressed against the pad, and means to remove from the belt, ink wiped thereon by the die.

16. In a press for printing engraved stationery, a die wiper pad, an endless die wiper belt contacting the pad, a pair of opposed rollers contacting opposite sides of the belt in advance of the pad, adjustable means to press the rollers toward each other and against opposite sides of said belt, means to rotate one of said rollers to advance said belt forwardly past the wiper pad, a second pair of opposed rollers in back of the wiping pad and contacting opposite sides of the belt, means to press said second pair of rollers toward each other against opposite sides of the belt, means to rotate one of said second pair of rollers at a peripheral speed less than that of the first pair of rollers, to feed the belt forwardly toward the wiper pad, whereby the portion of the belt moving forwardly from the second pair of rollers to the first pair of rollers, is under greater tension than the remaining portion of the belt, a die, means to wipe the die against the portion of the belt which is pressed against the pad, and means to remove from the belt, ink wiped thereon by the die, said means for removing ink from the belt comprising means to apply solvent to a tensioned portion of the belt between the pad and the first pair of rollers.

17. In a press for printing engraved stationery, a die wiper pad, an endless die wiper belt contacting the pad, a pair of opposed rollers contacting opposite sides of the belt in advance of the pad, adjustable means to press the rollers toward each other and against opposite sides of said belt, means to rotate one of said rollers to advance said belt forwardly past the wiper pad, a second pair of opposed rollers in back of the wiping pad and contacting opposite sides of the belt, means to press said second pair of rollers toward each other against opposite sides of the belt, means to rotate one of said second pair of rollers at a peripheral speed less than that of the first pair of rollers, to feed the belt forwardly toward the wiper pad, whereby the portion of the belt moving forwardly from the second pair of rollers to the first pair of rollers, is under greater tension than the remaining portion of the belt, a die, means to wipe the die against the portion of the belt which is pressed against the

pad, and means to remove from the belt, ink wiped thereon by the die, said means for removing ink from the belt comprising means to scrape ink from a tensioned portion of the belt between the pad and the first pair of rollers.

5 18. In a press for printing engraved stationery, a die wiper pad, an endless die wiper belt contacting the pad, a pair of opposed rollers contacting opposite sides of the belt in advance of the pad, adjustable means to press the rollers toward each other and against opposite sides of said belt, means to rotate one of said rollers to advance said belt forwardly past the wiper pad, a second pair of opposed rollers in back of the 10 wiping pad and contacting opposite sides of the belt, means to press said second pair of rollers toward each other against opposite sides of the belt, means to rotate one of said second pair of rollers at a peripheral speed less than that of the first pair of rollers, to feed the belt forwardly toward the wiper pad, whereby the portion of the belt moving forwardly from the second pair of rollers to the first pair of rollers, is under greater tension than the remaining portion of the belt, 15 a die, means to wipe the die against the portion of the belt which is pressed against the pad, and means to remove from the belt, ink wiped thereon by the die, said means for removing ink from the belt comprising means to scrape ink from a tensioned portion of the belt between the pad and the first pair of rollers, and means to apply solvent to a tensioned portion of the belt between the pad and the first pair of rollers, which has been scraped.

20 19. In a press for printing engraved stationery, a die wiper pad, an endless die wiper belt contacting the pad, a pair of opposed rollers contacting opposite sides of the belt in advance of the pad, adjustable means to press the rollers toward each other and against opposite sides of said belt, means to rotate one of said rollers to advance said belt forwardly past the wiper pad, a second pair of opposed rollers in back of the 25 wiping pad and contacting opposite sides of the belt, means to press said second pair of rollers toward each other against opposite sides of the belt, means to rotate one of said second pair of rollers at a peripheral speed less than that of the first pair of rollers, to feed the belt forwardly toward the wiper pad, whereby the portion of the belt moving forwardly from the second pair of rollers to the first pair of rollers, is under greater tension than the remaining portion of the belt, 30 a die, means to wipe the die against the portion of the belt which is pressed against the pad, and means to remove from the belt, ink wiped thereon by the die, said means for removing ink from the belt comprising means to scrape ink from a tensioned portion of the belt between the pad and the first pair of rollers, and means to apply solvent to a tensioned portion of the belt between the pad and the first pair of rollers, which has been scraped.

35 20 19. In a press for printing engraved stationery, a die wiper pad, an endless die wiper belt contacting the pad, a pair of opposed rollers contacting opposite sides of the belt in advance of the pad, adjustable means to press the rollers toward each other and against opposite sides of said belt, means to rotate one of said rollers to advance said belt forwardly past the wiper pad, a second pair of opposed rollers in back of the 40 wiping pad and contacting opposite sides of the belt, means to press said second pair of rollers toward each other against opposite sides of the belt, means to rotate one of said second pair of rollers at a peripheral speed less than that of the first pair of rollers, to feed the belt forwardly toward the wiper pad, whereby the portion of the belt moving forwardly from the second pair of rollers to the first pair of rollers, is under greater tension than the remaining portion of the belt, 45 a die, means to wipe the die against the portion of the belt which is pressed against the pad, and means to remove from the belt, ink wiped thereon by the die, and intermeshing gears on said first pair of rollers.

50 21 19. In a press for printing engraved stationery, a die wiper pad, an endless die wiper belt contacting the pad, a pair of opposed rollers contacting opposite sides of the belt in advance of the pad, adjustable means to press the rollers toward each other and against opposite sides of said belt, means to rotate one of said rollers to advance said belt forwardly past the wiper pad, a second pair of opposed rollers in back of the 55 wiping pad and contacting opposite sides of the belt, means to press said second pair of rollers toward each other against opposite sides of the belt, means to rotate one of said second pair of rollers at a peripheral speed less than that of the first pair of rollers, to feed the belt forwardly toward the wiper pad, whereby the portion of the belt moving forwardly from the second pair of rollers to the first pair of rollers, is under greater tension than the remaining portion of the belt, a die, means to wipe the die against the portion of the belt which is pressed against the pad, and means to remove from the belt, ink wiped thereon by the die, and intermeshing gears on said first pair of rollers.

ROBERT N. STEFFENS.
